WAIST BAND ADJUSTMENT FOR GARMENTS

Harry E. Miller, East Cleveland, Ohio

Application May 22, 1936, Serial No. 81,222

1 Claim. (Cl. 2-237)

This invention relates, as indicated, to a waistband adjustment for garments, but has reference more particularly to an adjustment of this character which is particularly adapted for use in 5 the manufacture of men's trousers.

One of the principal objects of the invention is to provide novel and efficient means for adjusting the waistband while preserving the normal contact and avoiding the production of an 10 unsightly gap between the top and bottom facings of the pocket.

A further object of the invention is to provide means for adjusting the waistband, without in 15 any way mutilating the waistband or encumbering the same with unsightly appearing flaps, gussets and similar devices commonly employed for waistband adjustment.

To the accomplishment of the foregoing and related ends, said invention, then, consists of the 20 means hereinafter fully described and particularly pointed out in the claim; the annexed drawing and the following description setting forth in detail one method constituting, however, but one of various applications of the principle 25 of my invention.

In said annexed drawing:—

Fig. 1 is a side elevation of the upper portion of a pair of trousers embodying the invention; Fig. 2 is a view similar to Fig. 1, but with a portion of the waistband and fly turned back; Figs. 30 3, 4 and 5 are fragmentary cross-sectional views, taken on the lines 3—3, 4—4 and 5—5, respectively of Fig. 1.

Referring more particularly to the drawing, 35 1 and 1a represent the front and rear sections respectively of a pair of trousers, said sections forming a side seam S. The trousers have a side pocket 3 having an entrance opening at said side seam, the seam terminating below the upper 40 end of said opening to form a placket. The term "placket" is here used in its ordinary sense, being defined as a finished opening or slit from the top of a garment to facilitate putting it on and taking it off. The trousers also have a waistband 2 attached thereto, a portion of said waistband being attached to the front section of the 45 trousers and a portion being attached to the rear section of the trousers, the front portion outwardly overlapping the rear portion, as clearly shown in Fig. 3.

The sides of the front portion of the waistband 2 are extended, without break or seam, to the point indicated by numeral 4, which is substantially beyond the upper end 5 of the pocket opening. The extensions 6, which are thus

formed, are each provided with a buttonhole 7, which engage any one of a series of three buttons 8, 9 and 10. The buttons 8, 9 and 10 are secured to the sides of the rear portion of the waistband 2 and are arranged in longitudinal alignment with such waistband. The purpose of these buttons is to permit adjustment of the waistband to a size both larger and smaller than the "original draft" of the waistband, by which expression is meant the size of waist for which 10 the trousers are normally intended.

Secured to the lower edge of the extension 6, as by a line of stitching 11, is a piece 12, which extends from such lower edge to a point 13, which is somewhat below the upper end 5 of the 15 pocket opening. This piece is of substantially triangular shape, and its forward edge, which is substantially in alignment with the upper part of the pocket opening, is secured as by a line of stitching 14, to the edge of the bottom facing 15 20 of the pocket. Above the point 5, the forward edge of the piece is stitched not only to the bottom facing 15 of the pocket, but the top facing 16, as well. The rear edge 17 of the piece 12 is curved, as shown in Figs. 1 and 2. The piece 12 25 thus forms a flap adapted to overlie the rear section of the trousers.

The "original draft" is provided when the button 9 engages the buttonhole 7, the button 9 being located midway between the buttons 8 and 10. In this condition of the trousers, the top facing of 30 the pocket will lie smoothly against the bottom facing thereof and the piece 12 will lie smoothly against the area 18 of the trouser, which it overlaps.

In adjusting the waistband to a smaller size than the "original draft", the button 10 will engage the buttonhole 7, and in adjusting to a larger size, the button 8 will be caused to engage such buttonhole.

The rear portion of the waistband thus has a plurality of fastening means at the sides, and the extension of the front portion of the waistband has a single fastening means adapted to selectively engage any one of the fastening means on the rear portion of the waistband to hold the parts together and to provide adjustability of the waistband and the garment. The fastening means, it will be noted, are exteriorly accessible, so that adjustments can be made 45 quickly and easily.

The lower end 13 of the piece 12 constitutes in effect a pivotal point about which the extension 6 and piece 12 rotate during the aforesaid adjustments of the waistband, and due to the fact 50 55

that this pivotal point is considerably below the upper end of the pocket opening, and also to the fact that the piece 12 is secured to the edge of the pocket 3, the aforesaid adjustments may be 5 accomplished without disturbing the smooth contact between the top and bottom facings of the pocket and without producing unsightly gaps or bulging in the vicinity of the pockets. Moreover, the employment of a piece of this character avoids mutilation of the waistband and avoids 10 encumbering of the waistband proper with unsightly appearing flaps, gussets and similar devices commonly employed for waistband adjustment. The piece, furthermore, constitutes a reinforcement between the waistband and pocket and serves to preserve the life of the pockets.

Although the waistband extension and piece 12 have been described with reference to a pair of trousers provided with pockets, it is to be understood that these novel features may be embodied with advantage in other garments, such as skirts, shorts, pajamas, etc., having side openings instead of pockets.

Other forms may be employed embodying the 25 features of my invention instead of the one here explained, change being made in the form of construction, provided the elements stated by the following claim or the equivalent of such stated elements be employed, whether produced 30 by my preferred method or by other embodying

steps equivalent to those stated in the following claim.

I therefore particularly point out and distinctly claim as my invention:—

A garment having front and rear sections to 5 form a side seam, a side pocket with an entrance opening at said seam, said seam terminating below the upper end of said opening to form a placket, a waistband attached to said garment having a portion attached to the front section 10 thereof and outwardly overlapping another portion that is secured to said rear section, the overlapping portion forming an extension that extends beyond the upper end of said pocket opening, a substantially triangular piece secured to 15 the lower edge of said extension and having one side secured to the edge of the bottom facing of said side pocket and to the garment above said pocket, forming a flap adapted to overlie the rear section of said garment; said rear portion of the 20 waistband having a plurality of fastening means at the side and said extension of the front portion of the waistband having a single fastening means adapted to selectively engage any one of said first-named fastening means to hold the 25 parts together and to provide adjustability of the waistband and the garment, said fastening means being exteriorly accessible.

HARRY E. MILLER. 30
